METHOD OF AND MEANS FOR FEEDING
SHEET MATERIAL

Arthur Wormser, Offenbach, near Frankfort-on-the-Main, Germany

Application March 14, 1935, Serial No. 11,021
In Germany October 19, 1932

5 Claims. (Cl. 271—58)

The invention relates to a method of and means for feeding sheet material to a printing or other machine, and the new feature is that the side aligning gauge is timed so as to engage and align each sheet at the moment when the back end of the overlapping top sheet has just passed said mark.

One great advantage of this arrangement is that the usual side aligning gauge which has answered all requirements of practice can be used.

On the accompanying drawing my invention is illustrated by way of example,

Fig. 1 being a side elevation of the feed table showing the relative position of the sheets at a moment when the top sheet is passing to the impression cylinder or other device, but has not entirely passed the side gauge.

Fig. 2, a similar elevation to Fig. 1 showing the position of the sheets after the top sheet has left the side gauge, and the second sheet is being aligned sideways.

Fig. 3, a similar view, at the moment when the third sheet has just reached the side gauge, and

Fig. 4, a similar view, after the second sheet has been released from the front gauges and has commenced its movement towards the impression cylinder, or other device, to which it has to be fed.

In Fig. 1 the sheet 1 is the top sheet which has been previously aligned and is being taken over by the machine. The back end of this sheet 1 overlaps the sheet 2 which has just reached the front gauges 4. This second sheet 2 overlaps the underlying sheet 3 which slowly advances together with the following sheets in the same spaced relation. The normal side gauge 5 is open, so that, the sheet 2 can be aligned against the front gauges 4, and the back end of the sheet 1, can pass freely.

According to Fig. 2 the overlapping top sheet 1 has advanced so far towards the machine that the side gauge 5 can close and effect the side alignment of the sheet 2. Meanwhile the sheet 3 and the following sheets have advanced, but the overlapping relation and the feeding speed are so chosen that the front edge of the sheet 3 does not reach the side gauge 5 before the side alignment of the sheet 2 is finished.

Fig. 3 shows the moment when the side alignment of the sheet 2 is just completed. The side gauge 5 has opened again. The sheet 3 and the following sheets have advanced so far that the front end of the sheet 3 has reached the side gauge 5. The back end of the sheet 1 which

previously overlapped the front end of the sheet 2, has now passed beyond the front gauges 4.

At this moment the front gauges 4 liberate the perfectly aligned sheet 2, as shown in Fig. 4, so that it is taken over by the machine. The sheets 1, 3 etc. have continued their motion forward.

The front gauges 4 now rise again, in order to stop and align the following sheet 3, while the back end of the sheet 2 overlaps the front gauges 4 and the sheet 3, as shown in Fig. 1 for the previous sheet. The cycle of operation is then repeated.

It is not absolutely necessary for the sheet 3 and the following sheets to be advanced under the sheet 2 in a scale-like formation, although this arrangement has advantages in practice. The claims cover the arrangement in which that part of the sheet which lies between the side aligning gauge and the front gauges is overlapped by the back end of the previous sheet during the time, or a part of the time, in which the alignment of said sheet takes place. It is immaterial in what way this overlapping is obtained.

Instead of a side-pull gauge any other side aligning gauge can be used. For the invention it is only essential that the commencement of the side-aligning, the back end of the previous sheet has just passed the side gauge. Further, provision will be made for the following sheet only to reach the side gauge when the side alignment of the previous sheet has been effected. Although therefore the sheet 2 during the side alignment, or, at least, during a part of this operation, at the part in front of the side gauge 5, is overlapped by the sheet 1, and although it lies partly on underlying sheets, nevertheless all operations are so controlled that during the side alignment itself only the proper part of the sheet 2 will be engaged by the side gauge.

What I claim and desire to secure by Letters Patent of the United States is:

1. A method of registering sheets, consisting in advancing a continuous bank of seriated sheets towards registering means, front registering the top sheet of said bank, holding said sheet against further forward movement, side registering said sheet, front registering the succeeding underlying sheet, removing said top sheet, and side registering said underlying sheet while still partly covered by said top sheet.

2. A method of registering sheets, consisting in advancing a continuous bank of seriated sheets towards registering means, front registering the top sheet of said bank, holding said sheet against

5 further forward movement, side registering said sheet, front registering the succeeding underlaying sheet, removing said top sheet, and side registering said underlaying sheet while still partly covered by said top sheet, and immediately after the rear edge of the latter sheet has passed the side registering means.

10 3. A method of registering sheets, consisting in advancing a continuous bank of seriated sheets towards registering means, front registering the top sheet of said bank, holding said sheet against further forward movement, side registering said sheet, front registering the succeeding underlaying sheet, removing said top sheet, and side registering said underlaying sheet while still partly covered by said top sheet, and immediately after the rear edge of the latter sheet has passed the side registering means.

15 4. A method of registering sheets, consisting in advancing a continuous bank of seriated sheets towards registering means, front registering the top sheet of said bank, holding said sheet against further forward movement, side registering said sheet, front registering the succeeding underlay-

ing sheet, removing said top sheet, side registering said underlaying sheet while still partly covered by said top sheet, and immediately after the rear edge of the latter sheet has passed the side registering means, and completing the side registering of said underlaying sheet before its succeeding underlaying sheet reaches said side registering means.

5 5. A method of registering sheets, consisting in advancing a continuous bank of seriated sheets 10 towards registering means, front registering the top sheet of said bank, holding said sheet against further forward movement, side registering said sheet, front registering the succeeding underlaying sheet, removing said top sheet, side registering said underlaying sheet while still partly covered by said top sheet, and immediately after the rear edge of the latter sheet has passed the side registering means, and completing the side registering of said underlaying sheet before its succeeding underlaying sheet reaches said side registering means.

15 20 ARTHUR WORMSER.
